UNITED STATES PATENT OFFICE.

WILLIAM E. ELLIOTT, OF GRAND RAPIDS, MICHIGAN.

BUTTON-SETTING MACHINE.

1,147,381.

Specification of Letters Patent.

Patented July 20, 1915.

Original application filed August 19, 1912, Serial No. 715,974. Divided and this application filed May 9, 1913, Serial No. 766,660. Renewed October 19, 1914. Serial No. 867,535.

To all whom it may concern:

Be it known that I, WILLIAM E. ELLIOTT, a citizen of the United States of America, residing at Grand Rapids, in the county of Kent and State of Michigan, have invented certain new and useful Improvements in Button-Setting Machines; and I do hereby declare the following to be a full, clear, and exact description of the invention, such as 10 will enable others skilled in the art to which it appertains to make and use the same.

My present invention relates to button setting machines and particularly to the type of such machines, which is described 15 in my co-pending application Serial No. 715,794, filed August 19, 1912, from which the subject matter of this present application is divided.

The object of the present invention is, generally, to provide an improved mechanism whereby buttons may be securely attached to shoes; and, more particularly, to provide an improved means for "feeding" such buttons into the proper position where- 20 in they may be so attached; improved means for forming the button-attaching staples; improved means whereby these staples with their buttons may be fastened to the shoes; improved means for preventing the acci- 25 dental breaking of the buttons or the dam- aging of the machine by any imperfect op- eration of the parts; improved means where- by the machine may be automatically locked 30 from operation when no button is in posi- tion to be attached to the shoe; and to pro- 35 vide the machine with improvements in other respects hereinafter appearing. These objects I attain by, and my present in- 40 vention is preferably embodied in, the struc- ture hereinafter described and illustrated by the accompanying drawings, in which:—

Figure 1 is a side elevation, partly in vertical section, of a portion of my button-attaching machine and illustrating my present 45 invention; Fig. 2 is a like view of parts of the same and illustrating the movable mem- bers in another position; Figs. 3, 4, 5 and 6 are plan views in a plane indicated by the line 3—6 of Figs. 1 and 2 (the upper por- 50 tion of the machine being removed), illus- trating different successive positions of cer- tain parts in their operative movements; Fig. 7 is a side elevation of the greater part of the structure shown in Fig. 1, viewed

from the opposite direction; Fig. 8 is a view 55 similar to Figs. 3, 4, 5 and 6, showing a portion of the locking mechanism whereby the machine is held from operative move- 60 ment; Fig. 9 is a view of parts of the locking mechanism shown in transverse section on line 9—9 of Fig. 8; and Fig. 10 is a cross- section of the button chute, on line 10—10 of Fig. 2.

The buttons 1 slide by gravity down the inclined button-chute 2, the body of each 65 button being supported by the side members 3 of the chute and the eye 4 of the button entering a longitudinal slot between the side members as particularly shown in Fig. 10. These buttons are held in the chute by a 70 spring pressed retainer 5 engaging the low- ermost button as shown in Figs. 1 and 2.

6 is a reciprocating slide which consti- 75 tutes the operating member of the machine and is reciprocated by any convenient means, preferably by a rod 7 connected to a suitable treadle (not shown) at its lower end and pivoted to one arm of a bell crank lever 8 at its upper end, the other arm of the lever being connected by a rod 9 to a 80 lug 10 on the slide 6. Carried by the slide 6 is a pivoted pusher 11, which at its lower end engages a sliding staple former 12 to move the same downward. This pusher is held in engagement with the former by a 85 fixed stop 14, comprising a stud and roller, until a projection 13 on the pusher engages the stop which now trips the pusher and swings the same out of engagement with the former. The former 12 slides between gibs 90 15 and 19 frictionally engaged with the former by a spring 16 to frictionally hold the former from moving. The gib 19 has an opening 18 through which the wire 20 is fed, and the corner 17 of the former co- 95 acting with the gib 19 shears the wire 20 therebetween; the distance between the gibs being equal to the length of wire required to form a staple 22. An anvil 23 is provided over which the staple is formed by the 100 former 12. The anvil also has longitudinal and transverse openings 45 to receive the eye of the button and guide the wire into the same. This anvil is preferably formed in one end of an oscillating bar 29 upturned 105 at its respective ends, pivoted near the middle, and extending beneath the slide 6 and the former 12. The ends of this bar are cut.

wardly inclined and engaged by inwardly inclined ends of the former to oscillate the bar as hereafter described.

The lower end of the former is recessed to receive the staple formed thereby, and provided with longitudinal grooves 24 to receive and guide the legs of the staple. A driver 25 is attached to the slide 6 and reciprocates in the former to engage and drive the staple. This driver has a slot in its end to receive the eye of the button and shoulders at each side of the slot to depress the crown of the staple at each side of the button eye. To yieldably force the former 10 against the fabric to which the button is attached the slide 6 carries a yieldable plunger 31 to engage the former after the pusher has been tripped from the same. This plunger is provided with a spring 32 to yieldably force the same downward, engaging a collar on the plunger at one end which limits the movement of the plunger downward, and provided at the upper end by a washer 20 slidable on the plunger and engaged by the divided end of the pivoted arm 42, carried by the slide 6, the free end of which arm is normally held against the spring by a rigid arm 51 projecting from the upper end of the said slide.

30 34 represents a rigidly supported clenching die, against which the legs of the staple are clenched inward as at 35 when forced through the fabric 33 by the driver 25. A pin 26 in the former has a limited movement 35 in a recess 27 in the bottom of the driver, and when the slide and driver move back to starting position the pin engages the shoulder at the end of the recess and carries the former back to starting position. To 40 feed the wire 20, an oscillating arm 36 is pivoted near its upper end, as at 38, and is moved backward by means of a lug 40 thereon engaged by a roller 39 on the slide 6, and is moved forward to feed the wire by 45 a lug 66 on the arm 42, which engages a bell crank arm 43 on the lever 36. A holding dog 44 is provided to prevent the wire 20 from moving backward, and a similar dog 41 is mounted on the arm 36 to force the 50 wire forward.

To place the buttons on the anvil 23, one by one, a bell crank lever 49 is provided which constitutes a part of the button feed mechanism of the machine. On this lever 55 is mounted a feed finger 46 pivoted at its upper end to the front arm of the lever as at 48, and having a concave lower end to engage the button. This finger is pressed downward upon the button by a spring 47 and as the lever 49 is oscillated the feed finger 46 is reciprocated to engage the lowermost button in the chute and carry the same downward and place it upon the anvil. On the upward movement of this finger, it is lifted and carried up over the

lower button, to prevent pushing the buttons upward in the chute, by means of a pin 58 projecting from the side of the finger, which pin slides along a guide 59 and engages a recess 60 in a pivoted plate 61, 70 yieldably held in position by a bifurcated and pivoted lever 62 engaging the edge of the plate at opposite sides of its pivot, and yieldably held against the same by a spring 55. This plate is rotated by the pin 58 and 75 carries the finger 46 upward and above the lowermost button, whereupon the pin leaves the recess and the finger is allowed to drop upon the button and the plate allowed to return to its normal position. On the down-stroke of the finger the pin pushes the plate away and the button carries the lower end of the finger. In the event that the finger should not get a button, it is desirable to 80 stop the wire feed and prevent making a 85 staple and driving the same without a button. To this end a lever 64, pivoted intermediate its ends, is provided, the inner end 65 of which extends within the path of the lug 66 when depressed, and is normally held 90 out of the path of the lug 66 by a spring above its outer end, as shown in Fig. 9, and is depressed by the rear end of the lever 49 when no button is under the finger 46.

To properly time the movements of the feed finger; to adapt its movement to various sizes of buttons, and to permit the bell crank lever to engage the stop lever 63 when the finger does not feed a button I provide the following mechanism: An independently pivoted arm 52 is connected at its movable end by a curved connecting rod 54 to a rod 53 which connects the lever 49 and the arm 51 on the slide 6. This arm 52 is also connected with the lever 49 by a spring 100 50, which spring tends to move the said lever downward toward the front of the machine and yields to the relative movement of the said arm and lever. The rod 53 engages a lug 57 on the lever 49 at one end 105 and the arm 51 at the other end, and is slotted at each end whereby it has a limited movement in each to properly time the movements of the feed finger 46. The spring 110 yields to adapt the movement of the finger 115 to different sizes of buttons, and when no button is under the finger the bell crank lever will move into contact with the stop lever and move the same to operative position.

120 A suitable housing, or frame 37, is provided for the device, in which the various parts are arranged.

In operation, as the slide 6 moves downward, the staple is formed and driven in a 125 manner readily understood by the foregoing description. During the first part of this movement the lug 57 traverses the slot in the rod 53, and the spring 50 swings the arm 52 downward and maintains the finger 46 130

in contact with the button. The relative movement of the arm 52 and the lever 49 now stops and the arm 51 traverses the slot in the other end of the rod 53 until the 5 working stroke is nearly completed; whereupon the arm 51 engages the lower end of the slot and swings both the arm 52 and lever 49 about their common axis and carries the finger back to a position to engage the 10 lower button in the chute on the commencement of the return stroke.

If buttons of different sizes are engaged, the spring 50 will yield to accommodate the position of the finger when resting on the 15 same. If no button is under the finger when it moves down, it is free to move beyond the normal position and the rear arm of the lever 49 will then rise far enough to engage the outer end 63 of the stop lever 64 and 20 throw its inner end 65 down within the path of the lug 66, whereupon the same is prevented from engaging and operating the wire feed lever 36, and thus no wire will be fed by the machine, when no button is in 25 position to receive the same. When the lug 66 so engages the lever, the spring 32 yields and permits the lever 42 to swing downward and the slide 6 to return to proper starting 30 position. This return movement causes the next button feeding motion of the feed finger to take place, which occurs shortly before the completion of the return stroke of the slide 6, the stop lever now being out 35 of the way of the lug 66. As the slide 6 completes its return stroke the wire feed is operated thereby as usual.

What I claim is:—

1. A button setting machine, comprising a reciprocable operating slide, a relatively 40 slideable staple former, a pusher pivoted on the slide engaging the former, a projection on the pusher, a fixed stop to engage the projection and disengage the pusher, a spring-pressed plunger carried by the slide 45 to engage the former after the pusher has been disengaged, and gibs frictionally engaging the former to temporarily hold the same from moving.

2. A button setting machine, comprising a slideable staple former, means for moving the former in two opposite directions, a gib to frictionally engage the former and temporarily hold the same from moving, and a spring engaging the gib and forcing the 55 same in contact with the former.

3. A button setting machine, comprising a reciprocable operating slide, a relatively 60 movable staple former, a driver fixed to the slide and also connected to the former to move the same in one direction and having a limited movement relative thereto, a pusher on the slide engaging the former to positively move the same in the opposite direction, means for disengaging the pusher, and a yieldable plunger on the slide to move the

former after the pusher has been disengaged from the same.

4. A button setting machine, comprising a reciprocable former, a slide carrying a pusher and a yieldable plunger successively 70 operating to move the former, a driver slideable in the former and attached to the slide and also having a slot or recess, a pin fixed in the former and having a limited movement in the said slot or recess, and means 75 for reciprocating the slide.

5. A button setting machine, comprising a reciprocable slide, a relatively slideable former, a pivoted pusher carried by the slide to engage the former while forming a 80 staple, a yieldable plunger carried by the slide to engage the former while the machine is clenching a staple, a driver slideable in the former connected to the slide and also connected to the former by a pin having a 85 limited movement relative to the driver, a rocker bar extending beneath the driver and having oppositely inclined ends arranged to be alternately engaged by like inclined ends on the driver, and an anvil carried on one 90 end of the bar and having an opening to receive the eye of a button and to receive a wire inserted in said eye.

6. A button setting machine, comprising a pivoted wire feeding arm, a slide carrying 95 a yieldable lug to operate the arm when feeding wire, a stop engaged by said lug to prevent the feeding movement of the arm and normally out of the path of the lug, and a button feed finger carried by a lever 100 adapted to move the stop into the path of the lug when the finger fails to convey a button to setting position.

7. A button setting machine, comprising an oscillating arm to feed wire, a reciprocable slide, an arm pivoted on the slide and arranged to operate the feeding arm on its feeding movement, a spring to hold the arm in operative position on the slide, a pivoted stop lever to intercept the movement of the 105 arm, a lever carrying a feed finger to move a button to setting position and limited in its movement by the button, and a spring to yieldably move said lever and finger beyond said position, said last named lever 110 engaging the stop lever to move the same to operative position when the movement thereof is not limited by a button.

8. A button setting machine, comprising a slide carrying a plunger to operate a 120 staple former, an arm pivoted on the slide, a wire feed device operated by the arm, a lug on the arm, a spring on the plunger engaging the arm to hold the same in operative position on the slide, a pivoted lever engaged by the lug and normally out of the path of the same, and means for moving said lever into the path of the lug when the machine fails to feed a button to setting position.

9. A button setting machine, comprising a reciprocable slide, an oscillating arm to feed wire, a bell crank member on the pivoted end of the arm, a projection on the side of the arm, a roller on the slide to engage the projection and move the arm backward, a pivoted arm on the slide to engage said member and move the wire feed arm forward, a lug on the last named arm, a spring to hold said arm in operative position on the slide, a pivoted stop lever normally out of the path of the lug, a bell crank lever arranged to engage the stop lever at one end, a spring to yieldably move said lever, and a feed finger carried by said lever and limited in movement by a button when held in setting position by the finger.
10. A button setting machine, comprising an anvil adapted to support a button in position to receive a wire, means for feeding a wire through the eye of the button, a feed finger to engage and carry a button to position on the anvil and limited in its movement by the button, a bell crank lever carrying the feed finger at one end, a spring to yieldably move said lever, and a stop to prevent feeding of the wire moved to operative position by the other end of the bell crank lever whenever the finger fails to carry a button into position on the anvil.
11. A button setting machine, comprising a pivoted lever, a feed finger carried by said lever, an anvil to receive the button and stop the movement of the lever, a pivoted
- arm, a spring connecting the arm and lever, a reciprocable operating slide, a rod connecting the lever and slide and having a limited movement relative to each to operate the lever during only a part of the movement of the slide, and a second rod connecting the first rod and the arm to vary the tension of the spring.
12. A button setting machine, comprising an anvil to receive and hold a button, wire feed mechanism to insert wire in the eye of the button, a stop lever to prevent the operation of said mechanism normally out of operative position, a bell crank lever, a feed finger carried by one end of said lever, the other end of said lever arranged to engage the stop lever and move the same to operative position when the finger does not engage a button, a pivoted arm, a spring connecting the arm and lever to move the lever, a reciprocable operating slide, a rod connecting the lever and slide and having a limited movement relative to each to operate the lever during only a part of the movement of the slide, and a second rod connecting the first rod and the arm to vary the tension of the spring.

In testimony whereof I affix my signature in presence of two witnesses.

WILLIAM E. ELLIOTT.
